UNITED STATES PATENT OFFICE.

LAURENCE A. HAWKINS, OF SCHENECTADY, NEW YORK, ASSIGNOR, BY MESNE ASSIGNMENTS, TO THE UNION SWITCH AND SIGNAL COMPANY, A CORPORATION OF PENNSYLVANIA.

RAILWAY SIGNALING SYSTEM.

1,126,206.

Specification of Letters Patent. Patented Jan. 26, 1915.

Application filed November 8, 1911. Serial No. 659,126.

To all whom it may concern:

Be it known that I, LAURENCE A. HAWKINS, a citizen of the United States, residing at Schenectady, in the county of Schenectady and State of New York, have invented certain new and useful Improvements in Railway Signaling Systems, of which the following is a specification.

My invention relates to electric signaling systems of the normal danger type, and particularly to signaling systems of this type in which the signals are controlled by alternating current and its object is to reduce to a minimum the number of line wires for the proper control of the signals.

I will describe two forms of signaling system embodying my invention and then point out the novel features thereof in claims.

20 In the accompanying drawings, Figure 1 is a diagrammatic view showing one form of signaling system embodying my invention. Figs. 2, 3 and 4 are vector diagrams showing the phase relations in certain of the relays of Fig. 1. Fig. 5 is a diagrammatic view showing a modification of the signaling system shown in Fig. 1 and embodying my invention. Figs. 6, 7 and 8 are vector diagrams showing the phase relations in certain of the relays of Fig. 5.

Similar reference characters refer to similar parts in each of the several views.

In the accompanying drawings I have shown my invention applied to home and distant systems of signaling, that is, to systems in which the signals are adapted to indicate "danger", "caution" and "clear," although its applicability is not limited to systems of this character. As here shown 40 the signals are of the one-arm three-position type but it is understood that any type of signal adapted to give the three indications may be employed equally well.

In normal danger signaling systems, as 45 is well understood, the signals are usually in the danger position of indication, and are moved to the clear and caution position only when they are approached by a car or train provided no car or train is within the 50 territory governed by such signals and when the car or train passes the signals they are returned to their danger position.

One feature of a signaling system embodying my invention is the provision of a 55 line relay of the two-winding type for each

block section for the control of the signal or signals governing that block section, the windings of these relays being supplied with currents of such relative phases that the signal for the block section directly in advance of a car or train will be moved to clear position and the signal for the second block section in advance of the car or train will be moved to the caution position, and that the signals for the succeeding block sections will not be affected by such car or train.

Referring now to Figs. 1 and 5 of the accompanying drawings, I have shown in each view a portion of a railway divided into block sections, 10, 11, 12, etc., which block sections are governed respectively by signals S, S', S'', etc. As here shown, these signals are controlled by track circuits arranged in accordance with the system disclosed in my copending application, Serial No. 511,663 filed August 7, 1909. In this system each track circuit includes two track relays, A, B, A', B', etc., for the control of the caution and clear positions of the signal for the corresponding block section. Each of these track relays comprises two windings one of which is connected with the track rails and the other with an independent source of current. Each track circuit is supplied with alternating signaling current from a transformer 14, 15 or 16, etc., the secondary of which is connected with the track rails and the primary of which may be connected with either of two sources 90 of current differing in phase by approximately 90°. One or the other of these sources is connected with the transformer of a block section by means of a circuit controller D, D', etc., operated by the signal 95 for the next succeeding block section, the arrangement being such that when a signal is in the danger position, currents of one phase will be supplied to the preceding track circuit, and when the signal is in the 100 caution and clear positions, current of the other phase will be supplied to the preceding track circuit. The line windings of each pair of track relays A, B, etc., are connected with sources of current differing by approximately 90° in phase, and the relation of the phases in these line windings to the phases supplied to the track circuit is such that when the next succeeding signal 105 is in the danger position, relay A will be 110

energized and relay B deenergized; and when the next succeeding signal is in the caution or clear position, both relays A and B will be energized. As here shown, I obtain the two phases differing by 90° from a three phase transmission line 17 by the use of transformers T, T', etc., connected in the well known three-phase two phase arrangement.

- 10 The explanation thus far given applies to both Figs. 1 and 5, and the portion of each of these systems thus far explained is similar to the normal clear system disclosed in my copending application Serial No. 15 511,663 herein before mentioned, hence no further explanation of this portion of either system is necessary.

Referring now to Fig. 1, I will explain the means herein shown for obtaining the 20 normal danger feature of control. In this view, in each of the transformers T, T', etc., I have shown a connection leading from the middle points of the secondaries, which connections are connected with the common wire O. By this arrangement of connections I obtain from each transformer four 25 phases differing by 90° . In the case of transformers T, T' and T², all four phases are not used, hence the terminals which are 30 not employed are left disconnected.

For each block section I provide a line relay R, R', R², etc., of the two-winding type each of which relays controls the operating 35 circuit of the signal mechanism for the corresponding block section. For example, the circuit for the caution position of signal S' may be traced as follows—from the left hand terminal of transformer T' through wire 22, armature 21 of relay R', wire 23, 40 front contacts and armature of track relay A', wire 24, signal S', wires 25 and 26 to the middle point of transformer T'; for the clear position of this signal the circuit is the same as just traced to the armature of relay 45 A', then through armature of track relay B', wire 27, signal S' to wires 25 and 26 and transformer T'. It will be seen therefore that when relay R' is open, signal S' is necessarily in the danger position, and that 50 when relay R' is closed, signal S' may be in danger, caution or clear position depending on track relays A' and B'.

As here shown the relays R, R', etc., are of the well-known polyphase induction 55 motor type, although I do not wish to limit myself to this specific type of relay, for any form of relay having two windings cooperating to close the contacts may be employed.

Each relay R, R', etc., comprises two field 60 windings 18 and 19, these windings being so arranged with relation to the stator of the relay that when the current in winding 19 leads the current in winding 18 the relay will be operated to close its armature contacts, but when the current in winding 18

leads that in winding 19 the armature contacts of the relay will be open or the relay will be given a reverse torque to hold these contacts open. Winding 19 of each relay R, R', etc., is connected with the adjacent 70 transformer T, T', etc., the connections being so arranged that the currents in these windings differ progressively by 90° ; that is, assuming the phase in winding 19 of relay R to be 0, the phase in the corresponding winding of relay R' is 90° , that in relay R² is 180° , in relay R³, 270° , and so on. This is clearly represented in the vector diagrams Figs. 2, 3 and 4, in which the lower vectors refer to the current and voltage in winding 19 of the corresponding relay, and the upper vectors refer to the current and voltage in winding 18 of the corresponding relay. An inspection of these vector diagrams will show that the reactance of the 85 circuit of winding 18 of each relay is relatively high, giving a large angle of lag of the current behind the voltage; and that the reactance of the circuit of winding 19 of each relay is relatively low because of the 90 non-inductive resistance 33 in series with the winding 19, giving a small angle of lag of the current behind the voltage.

The winding 18 of each relay may be connected with the transformer T, T', etc., for 95 the block section in the rear, the circuit including the back contacts of relay A for such block section in the rear, a reactance 34, which helps to give the current a large angle of lag, and a line wire 28 extending 100 throughout the block section. For example, the circuit for winding 18 of relay R' when energized by transformer T is as follows—from the left hand terminal of transformer T through wires 32 and 31, back contacts of 105 armature of relay A, reactance 34, wire 28, winding 18 of relay R', wire 29 to common wire O and middle of transformer T. For each signal I provide a circuit controller C, C', etc., operated by the signal in such manner that the circuit controller is open when the signal is in the danger position and closed when the signal is in either the caution or clear position. For each block section I provide contacts and conductors 115 adapted to connect line wire 28 extending through such section with line wire 28 extending through the block section in the rear; for example, the line wire 28 of block section 10 may be connected with line wire 120 28 of block section 11 by means of the following contacts and conductors:—Circuit controller C', wire 30, armature 20 of relay R'. It will be seen therefore that the current from transformer T may also pass 125 through winding 18 of relays R² and R³ provided signals S' and S² are in the caution or clear positions and relays R' and R² are closed. Windings 18 of relays R, R', etc., are so connected with the transformers 130

T, T', etc., that when these windings are each connected with the transformer for the block section immediately in the rear the phase of the currents in these windings differs progressively by 90° ; that is, assuming the phase of the current in winding 18 of relay R' to be 0, that in winding 18 of relay R² is 90° , in relay R³ is 180° , etc.

The operation of the system shown in Fig. 1 may now be explained as follows:— When a car or train W enters block section 10 as indicated, track relays A and B will both be opened, so that signal S indicates danger. The back contacts of relay A will close the circuit between winding 18 of relay R' and transformer T as hereinbefore described. The phase relations in the windings of relay R' will then be as indicated in Fig. 4, from which it will be seen that the current in winding 19 (C¹⁹) leads that in winding 18, (C¹⁸) and this relay, therefore remains closed, it having been closed when the car or train W enters the block section in the rear of block section 10, for reasons which will hereinafter appear. Track relay A' was already closed and track relay B' was open, so that signal S' therefore was in caution position. Circuit controller C' is therefore closed, so that line wire 28 of block section 10 is connected with wire 28 of section 11. Winding 18 of relay R² is thereby energized from transformer T, the phase of the current and voltage being the same as those in the corresponding winding of the relay R', as indicated by the vector diagram in Fig. 3. The phase of the current in winding 19 of relay R² is as indicated by C¹⁹ in Fig. 3, and since this current is ahead of the current in winding 18, relay R² is energized to close its contacts. Track relay A² being closed and track relay B² open, signal S² then moves to the caution position and in so doing it operates circuit controller D² to shift the phase of the current in the track circuit of block section 11 so that track relay B' will be energized to close its contacts. Signal S' therefore moves to the clear position, and the parts of the system will then be as shown in Fig. 1. When relay R² was energized, and signal S² moved to the caution position, winding 18 of relay R³ was connected with transformer T through circuit controller C², armature 20 of relay R², etc., the phase of the voltage and current in this winding being as indicated in the upper portion of Fig. 2. But the phase of the current in winding 19 of this relay is as indicated by C¹⁹ in Fig. 2, being therefore approximately 225° ahead of the current in winding 18, and since the sine of 225° is the same as the negative of sine 135° , it will be evident that the current in winding 19 lags behind that in winding 18 by approximately 135° and relay R³

will have a reverse torque tending to hold its armature contacts open. Hence signal S³ remains in the danger position. When the train W advances into block section 11, winding 18 of relay R³ will receive current from transformer T', which current is 90° in advance of that supplied to it by transformer T, hence the current in winding 19 will then lead that in winding 18 and relay R³ will therefore be energized to close its contacts thereby closing the caution position circuit for signal S³.

From the foregoing explanation of the system shown in Fig. 1, it will be seen that the essential feature of this system is the provision of a relay for each block section, each of which relays is so constructed and connected as to respond to current from the first and second block sections in the rear to close its contacts, but not to respond to current from the third block section in the rear. Hence I obtain the clearing of the signals two blocks in advance of a train but no further. I have also shown in Fig. 1 how the signal lamps may be controlled so that they will always be lighted when a train is approaching a signal but cut out at other times so as to save current and prolong the life of the lamp. The lamps are indicated at L, L', etc. The circuit of a lamp, for instance, that of lamp L' of signal S', is from left hand terminal of transformer T', wire 22, contact 21 of relay R', lamp L', wires 25 and 26 to common wire O. Thus the lamp L' is lighted when relay R' is energized and not otherwise, and, as I have shown, relay R' will always be energized when there is a train in block section 10, or in the section in the rear of block section 10. Thus, without additional line wires, the lamps are controlled so as always to be lighted when a train is approaching, and only then.

In the modification of my invention shown in Fig. 5, I employ a simpler arrangement of transformer connections, but two relays for each block section to control the clearing of the signals—a single phase relay, P, P', etc., and a polyphase relay R, R', etc. The operating circuit for each signal is controlled directly by the single phase relay P, P', etc., of the corresponding block section. The polyphase relay R, R', etc., of each block section is employed only to connect the line wire 28 extending through its block section with the line wire 28 of the block section in the rear, as in the system of Fig. 1. Each of these polyphase relays is, as here shown, of the induction motor type comprising two field windings 18 and 19 the power factors of whose circuits are substantially equal so that the angle of lag between the voltage and the current will be substantially the same in each winding. Winding 19 of each polyphase relay is con-

- nected with the transformer T , T' etc. of the corresponding block section in such manner that the phase of the current in these windings of adjacent relays differs by 5 90° . Thus, winding 19 of relay R is connected with the left hand terminal of transformer T , winding 19 of relay R' with the right hand terminal of transformer T' , winding 19 of relay R^2 with the left hand 10 terminal of transformer T^2 , and so on. This phase variation is represented dia- 15 grammatically by the lower vectors in the vector diagrams Figs. 6, 7 and 8. Winding 18 of each polyphase relay is connected in parallel with the winding of the single phase relay P , P' , etc., of the corresponding block section. As in the system of Fig. 1, a line wire 28 extends through each block section; the rear end of each line wire is 20 connected with the transformer T , T' etc. of the corresponding section through the back contacts of track relay A , A' , etc., and the other end of each line wire 28 is connected with the single phase relay and with 25 winding 18 of the polyphase relay for the next succeeding block section. Each line wire 28 will be connected with the line wire 28 of the block section in the rear when the signal for the corresponding block section 30 is in caution or clear position and when the polyphase relay R , R' , etc., of the corresponding section is energized, the connection between the two line wires including circuit controller C , C' , etc., wire 30 and 35 armature 20 of the polyphase relay. The connections of the line wires 28 to the trans- formers (through the back contacts of relays A , A' , etc.) are alternately arranged, so that the phase of the current in the line 40 wires of adjacent block sections, when the line wires are connected with the trans- formers of their own block sections, differs by 90° . Thus wire 28 extending through block section 10 is connected with the left hand 45 terminal of transformer T , and wire 28 of block section 11 is connected with the right hand terminal of transformer T' . Hence the phase of the currents in relays P , P' , etc., and in windings 18 of relays R , R' , etc., for adjacent blocks differ by 90° when the line wires which supply these windings are 50 connected directly with the transformers for the block sections in the rear respectively. Winding 19 of the polyphase relay 55 for each block section is connected with the phase opposite to that in winding 18 of the same relay when the line wire 28 which supplies such winding 18 is energized from the transformer for the block section in the rear. 60 It will now be clear that when the line wire 28 of a block section is connected with its transformer by the back contacts of relay A of that block section, the two windings 18 and 19 of the polyphase relay for the block 65 section next in advance will be energized

with currents differing by 90° in phase, hence this relay will be energized to close its contacts; and if the last mentioned line wire is then connected with the next succeeding line wire 28, the windings 18 and 19 of the relay for the second block section in advance will be energized with currents of substantially the same phase, hence no torque will be exerted upon the rotor of this relay and its contacts will remain open. 75

The operation of the system shown in Fig. 5 may now be explained as follows— When the block section in the rear of block section 10 is occupied by a car or train W , relay P' is closed, and track relay A' is 80 closed and track relay B' is open so signal S' indicates caution. When this car or train W enters block section 10 as indicated in the drawing, it opens track relay A , thereby connecting line wire 28 for this block with 85 transformer T . Winding 18 of relay R' is now energized from transformer T , the phase of the current in this winding being as indicated by C^{18} in Fig. 7; but winding 19 of this relay is already energized by current of the phase indicated by C^{19} in Fig. 7. Hence relay R' is energized to close its armature contacts 20. Circuit controller C' being closed, and line wire 28 of block section 10 is therefore connected with wire 28 of section 11 through circuit controller C' , wire 30 and armature 20 of relay R' . Relay P^2 is therefore energized, and the closing of its contacts causes signal S^2 to move to caution position. Winding 18 of relay R^2 is 90 also energized with current of the same phase as that in the corresponding winding of relay R' , as indicated by C^{18} in Fig. 6, but this phase is substantially the same as the phase of the current in winding 19 (indicated by C^{19} in Fig. 6) hence relay R^2 95 will remain open, and line wire 28 will not be connected with wire 28 of block section 12. The signals for the succeeding block sections will therefore not be affected. The 100 movement of signal S^2 to caution position operates circuit controller D^2 to shift the phase of the current in the track circuit of block section 11 so that track relay B' closes, causing signal S' to move to clear position. 105 When the car or train W advances into block section 11, it will cause track relay A' to connect the line wire 28 of this section with transformer T' . The currents in windings 18 and 19 of relay R^2 will then be displaced 90° in phase so that this relay will 110 be energized to close its contacts. The remainder of the operations will be the same as hereinbefore explained. 115

The main purpose of reactance 34 shown 125 in both Figs. 1 and 5 is to prevent a momentary short circuit when a train enters an unoccupied block. For instance, in Fig. 5, when the car or train W first enters block section 11, relay A' will be deenergized and 120 130

close its back contacts an instance before signal S' has time to open contact C' and before relay A can pick up and deenergize winding 18 of relay R'. Thus for an instant the following circuit is closed,—from right hand terminal of transformer T', back contacts of relay A', reactance 34, contacts 20 of relay R', wire 30, contact C' of signal S', wire 28 of block section 10, reactance 34 at the entrance of block section 10, back contacts of relay A, to left hand terminal of transformer T. Because of the reactance 34 this circuit has no effect, but if the reactances 34 were omitted this circuit would short-circuit transformers T and T' on each other during the short time required for signal S' to drop far enough to open contact C' or for relay A to pick up. As soon as contact C' or the back contacts of relay A open, transformer T is disconnected from, and transformer T' is left connected to, line wire 28 of block section 11, so that by the operations just described the circuit of relay P², when the car enters block section 11, is simply transferred from transformer T to transformer T' without being opened, and without relay P² being deenergized, even momentarily, so that no slow acting devices of any kind are needed to prevent signal S² from dropping from caution during the above described changes of connections. The same remarks (substituting R² for P²) apply to Fig. 1.

Although I have herein shown only two forms of railway signaling systems embodying my invention, it is understood that various changes and modifications may be made therein within the scope of the appended claims without departing from the spirit and scope of my invention.

Having thus described my invention, what I claim is:—

1. In a railway signaling system, a plurality of block sections, a signal for each block section, a line circuit for each block section, means in each block section controlled by the presence and absence of a car in the block section for supplying alternating current to the line circuit of the block section, the currents thus supplied to the several line circuits of any three successive sections being of different phases, signal controlling apparatus for each signal said apparatus being connected with the line circuit for the block section in the rear, contacts and conductors controlled by each signal controlling apparatus for connecting the line circuit of the corresponding block section with the line circuit of the block section in the rear, the signal controlling apparatus for each block section being responsive in its control of its signal to current of the phase supplied to the line circuits of the first and second block sections in the rear,

and not of the third block section in the rear.

2. In a railway signaling system, a plurality of block sections, a signal for each block section, a source of polyphase signaling current for each block section, a line circuit for each block section, means in each block section controlled by the presence and absence of a car in the block section for connecting the line circuit of the block section with a phase of the source of current for the same block section, the currents thus supplied to the several line circuits any of three successive sections being of different phases, a polyphase relay for the control of each signal each comprising two windings one of which is connected with a phase of the source of current for the corresponding block section and the other with the line circuit for the block section in the rear contacts and connections controlled by each polyphase relay for connecting the line circuit of the corresponding block section with the line circuit of the block section in the rear, each polyphase relay being responsive in its control of its signal and of its contacts to current in its line circuit winding of the phase supplied to the line circuit of the first and second block sections in the rear but not of the third block section in the rear.

3. In a railway signaling system, a plurality of block sections, a signal for each block section, a line circuit for each block section, means in each block section controlled by the presence and absence of a car in the block section for supplying alternating current to the line circuit of the block section, the currents thus supplied to the several line circuits of any three successive sections being of different phases, means for connecting the line circuit of each block section with the line circuit of the block section in the rear, and signal controlling apparatus for each signal connected with the line circuit for the block section in the rear and responsive in its control of its signal to current of the phase supplied to the line circuit of the first and second block sections in the rear and not of the third block section in the rear.

4. In a railway signaling system, a plurality of block sections, a signal for each section, signal-controlling apparatus for each block section for the control of the signal thereof, means for each block section for supplying a plurality of signaling currents differing in character, a line circuit for each block section connected with the signal-controlling apparatus of the next block section in advance, means controlled by the presence and absence of a train in each block section for connecting the line circuit of such block section with a source of current of one char-

acter for the block section, the currents thus supplied to the several line circuits of any three successive sections differing in character, and means for connecting the line circuits of adjacent block sections together, the signal controlling apparatus of each block section being adapted to respond in its control of its signal to current of the characters supplied to the line circuits of the two block sections in the rear but not of the third block section in the rear.

5. In a railway signaling system, a plurality of block sections, a signal for each block section, signal controlling apparatus for each block section, a line circuit for each block section connected with the signal-controlling apparatus for the next block section in advance, means for connecting the line circuits of adjacent sections together, and means controlled by the presence and absence of a train in each block section for supplying alternating current to the line circuit of such block section, the currents thus supplied to the several line circuits of any three successive sections differing in character, the signal-controlling apparatus for each block section being adapted to respond in its control of its signal to current from the two block sections in the rear and not from the third block section in the rear.

6. In a railway signaling system, a plurality of block sections, a line circuit for each block section, means controlled by the presence and absence of a car in each block section for supplying alternating current to the line circuit of the block section, the currents thus supplied to the line circuits of adjacent sections being of different phases, relays having windings connected to said line circuits, said relays being responsive or not to current in such circuits according to the phase of such current, means including contacts controlled by said relays for connecting the line circuits of adjacent block sections together, and signals for the block section controlled by said line circuits.

7. In a railway signaling system, a plurality of block sections, a source of polyphase signaling current for each block section, a line circuit for each block section, means controlled by the presence and absence of a car in each block section for connecting the line circuit of the block section with a phase of the source of current for the same block section, the currents thus supplied to the line circuits of adjacent sections being of different phases, a relay for each block section having two coöperating windings, one connected to the line circuit of the section in the rear and the other in a local circuit, the currents in said local circuits of the relays for adjacent block sections being of different phase, and means

including contacts controlled by said relays for connecting the line circuits of adjacent block sections together, and signals for the block sections controlled by the line circuits.

8. In a railway signaling system, a plurality of block sections, a signal for each block section, a line circuit for each block section, means controlled by the presence and absence of a car in each block section for supplying alternating current to the line circuit of the block section, the currents thus supplied to the line circuits of adjacent sections being of different phases, signal controlling apparatus for each signal, said apparatus being connected to the line circuit for the block section in the rear and being responsive or not responsive to current in such circuit according to the phase of such current, and contacts and connections controlled by each signal controlling apparatus for connecting the line circuit of the corresponding block section with the line circuit of the block section in the rear.

9. In railway signaling, a plurality of block sections, a line circuit for each section, means controlled by the presence of a train in each section for supplying alternating current to the line circuit for such section, the currents thus supplied to the line circuits of adjacent sections differing in phase, translating means for each section connected with the line circuit for the section in the rear, the translating means for each section being affected in one way or another according to the phase of the current which reaches it, means including contacts of the translating means for connecting the line circuits of adjacent block sections when the translating means is affected in one way, and signals for the sections controlled by said translating means.

10. In a railway signaling system, a plurality of block sections, a line circuit for each section, means for each section controlled by the presence of a car or train in the section for supplying alternating current to the line circuit for the section, the currents thus supplied to the line circuits for adjacent sections differing in character, signal-controlling apparatus for each section connected with the line circuit for the section in the rear and responsive or not to the current in such circuit according to the character of such current, means controlled by the signal-controlling apparatus for each section for connecting the line circuit for the section with the line circuit for the section in the rear, and signals for the sections controlled by said signal-controlling apparatus.

11. In a railway signaling system, a plurality of block sections, a line circuit for

each section, means for each section controlled by the presence of a car or train in the section for supplying alternating current to the line circuit for the section, the 5 currents thus supplied to the line circuits for adjacent sections differing in character, translating means for each section connected with the line circuit for the section in the rear and affected in one way or another 10 according to the character of the current in such circuit, means controlled by the translating means for each section for connecting the line circuit for the section with the line circuit for the section in the rear when the translating means is affected in one way, and signals for the sections controlled by said translating means.

In testimony whereof I affix my signature in presence of two witnesses.

LAURENCE A. HAWKINS.
